UNITED STATES PATENT OFFICE.

LON B. SNYDER, OF CHATTANOOGA, TENNESSEE.

BEDSTEAD-FASTENING.

No. 899,345.

Specification of Letters Patent.

Patented Sept. 22, 1908.

Application filed April 28, 1908. Serial No. 429,742.

To all whom it may concern:

Be it known that I, LON B. SNYDER, a citizen of the United States, residing at Chattanooga, in the county of Hamilton and State 5 of Tennessee, have invented new and useful Improvements in Bedstead-Fastenings, of which the following is a specification.

This invention relates to bedstead fastening, the object in view being to provide a 10 simple and effective fastening device for securing the side rails to the bed post in such manner as to provide a perfect fitting joint and adapt the rails to be interchangeably used and to be turned end for end so that 15 either side of the rail may be disposed upward.

With the above and other objects in view, the invention consists in the novel construction, combination and arrangement of parts 20 as herein fully described, illustrated and claimed.

In the accompanying drawings:—Figure 1 is a vertical sectional view of the bedstead fastening of this invention. Fig. 2 is a perspective view showing the fastening member carried by the bed post. Fig. 3 is a horizontal section through the combined fastening members.

In the drawings 1 designates a bed post 30 which, in carrying out the present invention is provided with a boss or enlargement 2 having a jointing face 3, while 4 designates one of the rails permanently connecting the head posts or the foot posts as the case may be.

One of the side rails is shown at 5 the same being of angle iron construction, or in other words provided with a flange 6 extending along one of the longitudinal edges thereof. Connected permanently to each end of the 40 side rail is a head 7 provided with a jointing face 8 adapted to fit tightly against the jointing face 3 of the boss 2 as shown in Fig. 3 in which it will be noted that the said jointing faces are reversely inclined from the center 45 outward, this not being essential however as said jointing faces may be described on a straight line.

The head 7 is provided with a slot 9 which extends from the jointing face 8 inward and from the top to the bottom of the head 7. 50 Within the slot 9, the head is provided with oppositely arranged inwardly extending projections 10 which are adapted to fit into oppositely arranged crooked grooves 11 in a tongue 12 projecting outward from the jointing face 3 of the boss 2, which tongue fits removably into the slot 9 of the head 7. The relation between the projections 10 and the grooves 11 is such that as the parts of the fastening device are brought together, the 60 jointing faces thereof are crowded into firm binding contact with each other, thereby providing a perfect joint between the fastening members and imparting rigidity to the bedstead as a whole. 65

I claim:

1. A bedstead fastening comprising in combination with a bed post and a detachable rail, a boss on the bed post provided with a jointing face, a tongue projecting 70 from said jointing face and provided in opposite sides with crooked grooves open at one end, and a head on the rail formed with a jointing face and a recess to receive said tongue and provided with projections in the 75 recess to engage the grooves in the tongue.

2. A bedstead comprising in combination with a bed post and a detachable rail, a boss on the bed post provided with a jointing face, a tongue projecting from said jointing face 80 and provided with a crooked groove open at one end, and a head on the rail formed with a jointing face and a recess to receive said tongue and provided with a projection in the 85 recess to engage the groove of the tongue, the relation between the separable parts of the fastening being such that the rail is rendered reversible.

In testimony whereof I affix my signature in presence of two witnesses.

LON B. SNYDER.
